UNITED STATES PATENT OFFICE

GEORGE LOOP MOORE AND JAMES ROBERT STEELE, OF OWEGO, NEW YORK

RAIL ANCHOR

Application filed April 23, 1930. Serial No. 446,511.

Our invention relates to improvements in rail anchors or anti-creeper devices for railroad rails.

The object of our invention is to provide a one-piece self-locking anchor which will grip the rail with great tenacity and prevent the creeping thereof.

Our invention comprises an anchor formed from a single piece of metal having the proper amount of resiliency which is bent at each end thereof and adapted to bear with considerable pressure against the rail above the flange at one side of the rail and against the edge of the flange at the other side of the rail when the anchor is applied to a rail.

The novel features of our invention will be more fully understood from the following description and claims taken with the accompanying drawing in which:

20 Fig. 1 is a side elevation of the anchor illustrating its initial position when applying it to a rail.

Fig. 2 is a side elevation of the anchor in its applied position on a rail.

25 Fig. 3 is an end view of the anchor as applied to a rail.

Referring to the drawing, 10 designates a rail supported on a tie plate 11 carried by a tie 12. An anchor made in accordance with 30 our invention, as shown in the drawing, comprises an under rail portion 13 having an inwardly bent flange overhanging portion 14 and an upwardly directed toe portion 15. The under rail portion 13 comprises at one 35 end a downwardly curved section 16 which continues in a loop upwardly to the flange overhanging portion 14 and at the other end a downwardly curved section 17 which continues in a loop upwardly to the toe portion 15.

40 A lip 18 may be provided on the inner vertical face of the toe portion 15. A substantially straight section 19 is preferably provided intermediate the sections 16 and 17. The end 20 of the portion 14 is preferably curved upwardly with a radius which is substantially equal to the radius of the fillet 21 which connects the flange 22 and the web 23 of the rail.

45 A substantially flat surface 24 is provided 50 on the anchor adjacent the portion 14. This

surface and the upper surface of the section 19 are so shaped and disposed with respect to each other that they will be brought into close contiguity with the upper surface of the rail flange and the under surface of the 55 rail base, respectively, when the anchor is applied to its effective position on the rail, as hereinafter set forth.

Our anchor is adapted to be applied to a rail adjacent the side of a tie by placing 60 it transversely thereon with the curved portion 20 abutting the surface of the rail in the vicinity of the fillet 21. The anchor is so shaped that when it is placed on the rail, in its initial position, as shown in Fig. 1, 65 the shortest distance between the curved surface 20 and the face 25 of the toe portion 15 is less than the shortest distance between the surface of the fillet 21 and the edge of the flange of the rail at the opposite side, and 70 preferably the distance between the curved portion 20 of the anchor and the section 19 is such that the anchor can be placed into its initial position on the rail with little effort; that is the curved portion 20 can be placed in 75 abutment with the fillet 21 without any material distortion of the anchor.

It will thus be seen from Fig. 1 that when the anchor is in its initial position it more or less hangs on the rail and the upper end 80 of the toe portion 15 is contiguous with the base of the rail at a point somewhat short of the contiguous edge of the rail base. When the anchor is struck a sharp blow with a hammer or other suitable implement at the 85 point 28 in the direction of the arrow the metal in the loop portion is sprung and the toe portion 15 snaps over the edge of the rail base as shown in Fig. 2 and the anchor thus distorted securely and effectively grips 90 the rail by virtue of its tendency to assume the condition from which it was sprung.

It will be noted that in this position the shortest distance between the curved surface 20 and the face of the toe portion 15 of the 95 anchor is greater than the distance between these same portions before the anchor is applied to the rail, so that, as the anchor tends to assume its normal condition, its resilient action presses the curved surface 20 against 100

the rail above the flange on one side and the face of the toe portion 15 firmly against the contiguous edge of the rail flange on the other side of the rail and therefore the anchor securely and effectively grips the rail.

- 5 When the anchor is in this position, that is as shown in Fig. 2, the upper surface 27 of the straight section 13 is in close contiguity with the under side of the base of the rail; the surface 24 is in close contiguity with the upper surface of the flange of the rail, and the under rail curved portions 16 and 17, which depend below the straight section 13, are so positioned that when the rail begins 10 to creep under service conditions the portions 16 and 17 will firmly engage the side face of the stationary tie 12 and the anchor will tend to tilt about a horizontal axis. This tilting action causes the upper surface 27 of the straight section 13 to press firmly and upwardly against the base of the rail while it causes downward pressure of the section 24 upon the upper surface of the flange of the rail, as well as a resultant increased pressure 15 of the face of the toe portion 15 against the contiguous edge of the base flange of the rail.
- 20
- 25

While we have shown our invention in but one form, it will be obvious to those skilled in the art that it is not so limited, 30 but is susceptible of various other changes and modifications without departing from the spirit thereof, and we desire, therefore, that only such limitations shall be placed 35 thereupon as are imposed by the prior art or as are specifically set forth in the appended claims.

Having thus described our invention what we claim as new and desire to secure by Letters Patent is:

- 40 1. A rail anchor comprising a toe portion adapted to engage the flange at one side of a rail, a fillet engaging portion adapted to normally grip the fillet at the other side of a rail, an under rail portion intermediate the aforementioned portions, comprising a tie 45 engaging portion and a portion adapted to lie substantially parallel with the under side of the base of a rail and in close contiguity thereto, and a substantially flat portion adjacent the fillet engaging portion adapted to lie substantially parallel with and in close 50 contiguity to the upper surface of the rail flange but normally out of gripping engagement therewith.

- 55 2. A rail anchor formed from a single bar of metal bent to form a body portion having depending under rail portions out of contact with the bottom of the rail base adapted to 60 engage a crosstie, a substantially straight portion intermediate the depending portions contiguous to the rail base but normally out of gripping engagement therewith and terminal arms of unequal length adapted to grip 65 the rail between the upper surface of the base

flange and the underside of the rail head at one side of a rail and the rail flange at the other side of the rail.

3. An integral anchor having an under rail portion adapted to lie in close contiguity to the under side of the base of a rail, a rail flange overhanging portion adapted to lie in close contiguity to the upper surface of one of the rail flanges but normally out of gripping engagement therewith, said rail flange 70 overhanging portion terminating in a rail engaging portion above its flange at one side of the rail and a toe portion extending from the under rail portion adapted to engage the opposite side of the rail, a part of the anchor 75 being deformable to bring the metal under stress during the placing of the anchor on the rail to effect a gripping action on the rail by said rail engaging portions.

4. An integral anchor comprising an under rail portion having a part thereof in close contiguity to the bottom of the base of a rail, a rail flange overhanging portion adapted to lie in close contiguity to the upper surface of one of the rail flanges but out of gripping engagement therewith, said rail flange overhanging portion terminating in a rail engaging portion between the upper surface of the base flange and the under surface of the rail head at one side of the rail and a toe portion 85 extending from the under rail portion adapted to engage the opposite side of the rail, a part of the anchor being deformable to bring the metal under stress during the placing of the anchor on the rail to effect a gripping action on the rail by said rail engaging portions.

5. An anchor comprising a portion adapted to engage the edge of a flange on one side of the rail, a portion adapted to engage the other side of the rail at a point above the flange of the rail, a portion adapted to lie in close contiguity to the upper surface of the flange of the rail, but normally out of gripping engagement therewith, an under rail portion adapted to lie in close contiguity to the base of the rail, but normally out of gripping engagement therewith, said contiguous portions adapted to be so disposed that they will simultaneously assume contiguous relation with the respective portions of the rail during the placement of the anchor on the rail.

6. An anchor comprising a pair of spaced curved under rail portions, a substantially straight portion intermediate said curved portions, a toe portion extending from one of the under rail portions, a rail flange overhanging portion connected to the other of said under rail portions and its free end radiused to engage the fillet between the web and base flange of a rail to which the anchor is to be applied, a flat portion adjacent the fillet engaging portion, said fillet engaging portions and toe portions being adapted to

- grip the rail upon application of the anchor thereto and said flat portion and said straight portion adapted to grip the rail due to the tilting action of the anchor upon the longitudinal movement of the rail.
5. 7. A one piece rail anchor comprising an under rail portion having a tie engaging portion and a portion adapted to lie contiguous to the under surface of the rail, a rail fillet engaging portion, a rail flange engaging portion and a portion in close contiguity to the upper surface of the flange of the rail.
10. 8. An anchor comprising a toe portion adapted to engage one side of a rail, a fillet engaging portion adapted to engage the fillet on the opposite side of the rail a portion adapted to lie contiguous to the upper surface of the rail-flange substantially throughout its width, and a plurality of intermediate resilient spaced loop portions one of which is deformable during placement of the anchor on a rail whereby a gripping action is effected on the rail by said toe and fillet engaging portions and a substantially straight portion intermediate said loop portions adapted to lie in close contiguity to the under side of a rail when the anchor is assembled therewith, said straight portion together with the portion which lies contiguous to the upper surface of the rail flange adapted to resist the tilting of the anchor.
15. 9. An anchor having a plurality of curved under rail portions adapted to engage a railroad tie, a substantially straight portion intermediate said portions, a portion adapted to engage the edge of the base flange at one side of a rail, a portion adapted to engage the fillet between the web and base flange at the other side of a rail, a portion in close contiguity to the flange of the rail adjacent said fillet engaging portion, said portion and the aforementioned straight portion adapted to grip the flange of the rail upon the longitudinal movement of the rail.
20. 10. An anchor comprising a toe portion adapted to engage the flange of a rail, a loop portion integral with said toe portion adapted to embrace the other flange of a rail and engage the rail at a point above the upper surface of the flange when the anchor is initially applied to a rail, said loop portion having at one end thereof a portion adapted to be brought into close contiguity to the upper surface of said flange and at the other end thereof a portion adapted to be brought into close contiguity to the under side of the rail base, upon the movement of the anchor to its operative position with respect to the rail.
25. 11. A rail anchor comprising a pair of tie engaging portions, one of said tie engaging portions terminating in a portion engaging the fillet of a rail and having a portion in close contiguity to the upper surface of the flange of a rail and the other portion engag-
- ing the opposite flange of the rail, and a member extending substantially parallel with the base of the rail connecting said tie engaging portions, said member adapted to lie in close contiguity to the under surface of the rail when the anchor is in its assembled position.
30. 12. An anchor comprising an under rail portion, a rail flange overhanging portion, and a rail flange edge engaging portion; said portions being disposed relatively to one another so that when the anchor is applied in its initial position to the rail, said overhanging portion engages one side of the rail at a point above the upper surface of the rail flange and said edge engaging portion is positioned at a distance short of the edge of the base flange on the other side of the rail and when the anchor is driven transversely of the rail it becomes distorted and in tending to assume its original shape grips the rail between the second and third mentioned portions and said under rail portion is in close proximity to the base of the rail at a point intermediate its edges and the overhanging portion is in close proximity to the upper surface of the base flange for a substantial distance toward its edge.
35. 13. An anchor comprising a rail flange edge engaging portion, an under rail portion, and a rail flange overhanging portion having an inner face disposed angularly with respect to the upper face of said under rail portion at an angle less than the slope of the upper surface of the rail flange, said portions being so disposed relatively to one another that when the anchor is applied initially to the rail said overhanging portion engages the rail at a point above the upper surface of its flange and the said edge engaging portion is positioned short of the edge of the rail flange and when the anchor is driven transversely of the rail it is distorted and in tending to assume its original shape grips the rail between the first and third mentioned portions and said faces snugly fit the rail flange.
40. 14. In a structure, a rail, means for supporting said rail, an anchor mounted on said rail in abutting relation to said means, comprising a portion exerting a pressure against the edge of the rail flange, a portion exerting a pressure against the rail at a point above the upper surface of the rail flange, a portion exerting a pressure downwardly against the latter surface, and a portion exerting a pressure upwardly against the underside of said flange at a point intermediate its edges.
45. 15. An anchor comprising a portion adapted to exert a pressure against the edge of a rail flange, a portion adapted to exert a pressure against the rail at a point above the upper surface of said flange, a portion adapted to exert a downward pressure on said surface throughout a substantial portion of its length, and a portion adapted to exert an upward

pressure against the underside of said flange at a point intermediate its edges.

16. An anchor comprising a portion adapted to exert a pressure against the edge of a rail flange, a portion adapted to exert a pressure against the fillet of the rail, a portion adapted to exert a downward pressure against the upper surface of the rail flange a substantial distance from the fillet engaging portion, and a portion adapted to exert an upward pressure against the underside of said flange at a point intermediate its edges.
17. An anchor comprising a portion adapted to exert a pressure against the edge of a rail flange, a portion adapted to exert a pressure against the rail at a point above the upper surface of said flange, a portion adapted to exert a downward pressure against said surface, and a portion adapted to exert an upward pressure against the underside of said flange intermediate its edges, said portions being so related to one another that said pressures are exerted simultaneously when the anchor resists the creeping action of the rail in service.
18. An anchor comprising a rail flange overhanging portion, an under rail portion and a rail edge engaging portion, said portions being so related to one another that when the anchor is applied initially to the rail, the end of the rail flange overhanging portion engages the rail at a point above the upper surface of the rail flange and the under side of the latter portion is disposed in spaced relation to the latter surface, the upper surface of the under rail portion is disposed obliquely with respect to the under surface of the base of the rail, the rail edge engaging portion is in spaced relation to the associated edge of the rail flange, and when the anchor is driven transversely onto the rail to its effective position, the last mentioned portion engages said edge of the rail, the under rail portion is brought into parallel relation with respect to said under surface of the base of the rail, and said rail flange overhanging portion engages the upper surface of the rail flange throughout a substantial portion of its length.
50. In testimony whereof we hereunto affix our signatures.

GEORGE LOOP MOORE.
JAMES ROBERT STEELE.
